OIL BURNING FURNACE WITH SEPARABLE
BURNER ASSEMBLY RINGS THEREFOR

Earl R. Baker, Windsor, N. C.

Application January 14, 1946, Serial No. 641,050

9 Claims. (Cl. 126—94)

1

This invention relates to oil burners and more particularly to an oil burner for economically, efficiently and simply heating a tobacco barn in which tobacco is gathered and cured prior to its use in the manufacture of tobacco products.

Heretofore tobacco barns have been heated by furnaces supplied manually with fuel although in some instances fuel burners have been used. However, these were complicated and expensive to manufacture and install and were inefficient probably because of their adaptations from house-heating units.

It is an object of the invention to provide a heater of low cost which will satisfactorily supply the necessary heat at a small cost.

Further objects and advantages of the invention will be apparent from the following description taken in conjunction with the accompanying drawings, wherein:

Figure 1 is a front elevation illustrating one application of the invention;

Fig. 2, a vertical section;

Fig. 3, a plan view of the burner without the hood;

Fig. 4, a perspective of the burner without the hood;

Fig. 5, a perspective of the deflector ring;

Fig. 6, a perspective of the burner ring and oil trough assembly; and

Fig. 7, a perspective of the base.

Referring to the drawings, the preferred form of the invention comprises a base consisting of lower and upper concentric rings 10 and 11 with inclined connecting members 12, the lower ring 10 being larger than the upper ring 11 and being adapted to rest upon a suitable support. The upper ring 11 is flanged to receive and support certain parts to be described. The connecting members 12 are spaced to permit the flow of air through the openings 12' therebetween.

On the base is mounted a burner ring and oil trough assembly comprising an inner annular channel or trough member 13 having a central opening or air passage 14' and an outer ring 14 connected to the inner annular channel member by a plurality of spaced V-shaped cups 15 separated by air vents 15'. Slots or notches 13' provide passageways in the outer rim of trough 13 to permit the oil from the trough to flow into the several cups 15. The outer ring 14 is preferably slightly taller than the rims of the trough. The burner and oil trough assembly may be cast as a unit or if desired may be formed of a plurality of parts.

A deflector ring 16 is supported on the outer 55 depending sleeve portion 29 which telescopes over

2

ring 14 by means of an outwardly extending circular flange 17, the external diameter of which preferably equals the external diameter of the outer ring 14. Since the body of the deflector ring 16 is of slightly less diameter than its flange, a space is provided above the flange 17 for pre-heating coils to be described. The deflector ring has a plurality of circumferentially spaced vanes 18 on the inner wall thereof and inclined relative to the vertical, these vanes being provided to produce a rotary or whirling movement of the products of combustion. Any desired means may be employed for maintaining the deflector ring in the desired position relative to the oil trough assembly so that each of the vanes of the deflector ring will be in alignment with one side of each V-shaped oil cup 15 of the assembly. To simplify the assembling of the deflector ring and the burner ring oil trough assembly, the outer ring 14 may be provided with a notch (not shown) for the reception of a projection (not shown) in the bottom of the flange 17.

Fuel to the burner ring is supplied by nozzles 19 from a fuel supply pipe 20 having a swivel joint 21 and a T connection 22. Supply pipe 20 is also coupled to a valve 23 and is connected by a T coupling 24 to the supply conduit 25. In order to improve the efficiency of the burner, the fuel is preferably preheated in its passage to the trough 13. This preheating is accomplished in the pipe 20 which is preferably wound several times around the exterior of the deflector ring above the flange 17. Thus the coils of pipe 20 are protected by the deflector ring and flange 17 from direct contact with the flames yet are exposed to radiant heat so that the fuel therein will be preheated. If desired a priming pipe 26 controlled by a valve 27 may be utilized for admitting fuel directly from the supply pipe 25 into the burner ring. The supply through the priming pipe may be shut off after the burner is in operation. The valves 23 and 27 may be provided with handle extensions (not shown) extending to the exterior of the tobacco barn or other building in which the device is located. The desirability of these handle extensions, permitting opening and closing of the valves from a distance, will be readily recognized when it is taken into consideration that the temperature within the tobacco barn or other building is maintained sufficiently high to be uncomfortable if not dangerous to the operator.

In order to provide a closed combustion chamber, a hood or flue 28 is utilized. Hood 28 has a

the flange 17 of the deflector ring, the outer burner ring 14 and the upper ring 11 of the base and rests upon the upper ends of the connecting members 12. The hood 28 is also provided with a door opening 30 adapted to be closed by a door 31 supported by a hinge 32, said door having a latch 33 for engagement with a catch 34. The door is preferably of a length corresponding to substantially one-half the circumference of the sleeve portion 29, as shown in Fig. 1, and is of a width substantially greater than the height of the burner ring oil trough assembly with the deflector ring mounted thereon. The door has the dimensions described to permit the interior of the furnace to be readily accessible so that the burner parts housed therein may be removed and replaced without removing the hood 28 and the flues to which it is connected.

Access may be had to the burner for lighting the same through the door, which is also provided with a draft regulator 35 which operates in the usual manner. The hood or flue casing 28 is supported at its outer end by a support 36 and has a tapered extremity 37 which snugly fits into one end of another flue 38 which has a connection with the chimney (not shown). An overflow pipe 39 is secured at one end by a jamb nut 40 screwed into an aperture 40' in the burner ring 14 near the top of an oil cup 15 so that in the event too much oil runs into the trough 13 it will flow into the cup and into pipe 39 and thereby will be led to a safe place outside of the barn.

It will be obvious to those skilled in the art that various changes may be made in the described form of the invention without departing from the spirit and scope thereof and therefore the invention is not limited by that which is shown in the drawings and described in the specification but only as indicated in the appended claims.

What is claimed is:

1. An oil burning furnace comprising a base of upper and lower rings with spaced supports connected between said rings and spaced to permit passage of air therebetween, a burner ring oil trough assembly mounted on said base and comprising an annular trough with an outer ring and intermediate spaced V-shaped connecting cups, a deflector ring mounted on said assembly, said deflector ring including inclined vanes on its inner surface, a hood having a depending sleeve housing said deflector ring and said assembly, a fuel supply pipe closely encircling said deflector ring and terminating adjacent the upper portion of said trough for discharging fuel thereinto, said deflector ring having each vane disposed substantially in alignment with one side of a corresponding intermediate cup, said burner ring having its outer side slightly taller than its inner side and provided with passageways in the outer rim of the annular trough for the flow of oil from the annular trough into the intermediate cups, and an overflow pipe for preventing over accumulation of oil in said annular trough.

2. An oil burning furnace comprising a base, a burner ring oil trough assembly mounted on said base and comprising an annular trough with an outer ring and intermediate spaced connecting cups, a deflector ring mounted on said assembly, said deflector ring including inclined vanes on its inner surface, a casing having a depending sleeve housing said deflector ring and said assembly, a fuel supply pipe closely encircling said deflector ring and terminating adjacent the upper portion of said trough for discharging fuel thereinto, said

deflector ring having each of its vanes disposed substantially in alignment with one of the sides of an intermediate cup, said burner ring being provided with passageways for the flow of oil from the annular trough into the intermediate cups.

3. An oil burning furnace comprising a base, a burner ring oil trough assembly mounted on said base and comprising an annular trough with an outer ring and intermediate spaced connecting cups, a deflector ring mounted on said assembly, said deflector ring including inclined vanes on its inner surface, a hood housing said deflector ring and said assembly, a fuel supply pipe for discharging fuel into the trough, said deflector ring having its vanes disposed substantially in alignment with corresponding sides of respective intermediate troughs, said burner ring being provided with passageways for the flow of oil from the annular trough into the intermediate cups.

4. An oil burning furnace comprising a base, a burner ring, a ring of fuel holding cups surrounding said burner ring, a deflector ring resting on said ring of cups, a hood housing said rings and provided with an opening through which said rings may be inserted and removed, a fuel supply pipe wound about the deflector ring and having its discharge end projecting into burner ring, whereby fuel will be preheated prior to its reaching the burner ring, and means including the deflector ring to protect the fuel supply pipe against direct contact with flames from the furnace.

5. An oil burner comprising a base ring having air intake openings therein; a burner ring comprising an annular trough, an annular outer wall surrounding said trough and spaced therefrom, radially disposed spaced cups between said annular trough and said outer wall arranged to receive fuel from said annular trough; and a deflector member supported on said burner ring comprising an annular wall having an outwardly extending annular flange at one end thereof and spaced therefrom, circumferentially spaced vanes carried internally thereof and spaced for respective disposition above said radial cups.

6. In an oil burner a burner ring comprising a circular trough, an outer wall about said trough and spaced therefrom, circumferentially spaced cups between said trough and said outer wall, means to permit flow of fuel from said trough to said cups, a deflector supported on said burner ring and comprising a substantially annular upright wall, and a plurality of angularly disposed deflector vanes along its interior spaced around said annular wall.

7. In an oil burner a burner ring comprising a circular trough, an outer wall about said trough and spaced therefrom, circumferentially spaced cups between said trough and said outer wall, means to permit flow of fuel from said trough to said cups, a deflector supported on said burner ring and comprising a substantially annular upright wall, and a plurality of angularly disposed deflector vanes along its interior spaced around said annular wall, said spaced cups having relatively broad bottom surfaces inclined from the horizontal.

8. An oil burning furnace comprising in combination a base having air openings in its sides and also being open centrally for passage of air upwardly, a burner ring oil trough assembly mounted on top of said base, said assembly comprising an annular trough surrounding a central air passage which continues the central opening of the base, a plurality of spaced cups ar-

ranged around the outer wall of the annular trough, means permitting oil in the annular trough to flow into the several spaced cups, the spaces between the cups providing a circumferential series of air vents for communication at their lower ends with the central opening of the base, an oil supply pipe discharging into said trough, a ring located above said assembly about which the supply pipe is coiled, said ring being so shaped and located as to protect the coiled pipe from direct contact with the flame of the furnace while permitting preheating of the oil passing therethrough, a valve to control flow of oil through said supply pipe, and a hood member enclosing said assembly and ring and providing also flue-connecting means.

9. The invention as set forth in claim 8 wherein the ring which protects the coiled pipe from contact with the flame is provided with a series of

vanes on the inner annular wall thereof, said vanes being inclined relative to the vertical and each vane being aligned with one of the walls of a cup, the arrangement being such that the vanes induce a whirling or rotary movement of the products of combustion.
